UNITED STATES PATENT OFFICE.

CHARLES E. POPE, OF HOLYOKE, MASSACHUSETTS, ASSIGNOR OF THREE-FIFTHS TO
B. F. PERKINS & SON, INCORPORATED, OF HOLYOKE, MASSACHUSETTS, A CORPORATION
OF MASSACHUSETTS.

PULP-SCREEN.

1,127,372.

Specification of Letters Patent.

Patented Feb. 2, 1915.

Application filed January 7, 1913. Serial No. 740,585.

To all whom it may concern:

Be it known that I, CHARLES E. POPE, a citizen of the United States of America, residing at Holyoke, in the county of Hampden and State of Massachusetts, have invented new and useful Improvements in Pulp-Screens, of which the following is a specification.

This invention relates to that class of apparatus used in screening paper pulp in paper making. Devices of the same general character have before been used,—for example, it is customary to provide a cylindrical, rotatable screen mounted to rotate, partly immersed in a shallow tank. The unscreened pulp is fed into the interior of the cylindrical screen and the latter is both rotated and vibrated to cause the pulp to pass from the screen cylinder to the tank from which it overflows into a desired receptacle. The agitation tends to keep the screen openings clear and cause the pulp to flow therethrough freely. A stream of water is directed through the openings in their upper travel to wash them clear of dirt, and means is provided to carry away the wash water without mixing it with the pulp yet to be screened.

The particular point of novelty in the present invention lies in the arrangement and operation of a structure whereby the old results may be accomplished in a better manner. This is accomplished primarily by rotating the cylindrical screen and vibrating the receptacle or tank in which the screen rotates. The agitation of the screen openings is thus accomplished with an extremely simple arrangement.

The object of the invention is to provide an improved apparatus of the class described, and with this object in view the invention will be described for the purpose of illustrating the preferred form.

In the drawings forming part of this application, Figure 1 is an end view showing the manner of mounting and vibrating the tank. Fig. 2 is a front view of one end only of the apparatus, the other end being broken away since it is essentially like the end shown.

The general arrangement of the rotatable screen and the flow of pulp to and from the apparatus is the same as specifically described in my co-pending application for

Letters Patent of the United States filed December 11, 1912 under Serial No. 736,171.

Referring to Fig. 2 of the drawings: The pulp enters the screen *b* through the pipe *a* and after it is screened passes from the tank *d* at the point *e* to any desired receptacle, not shown. The pipe *f* supplies the wash water directed through the screen openings in their upper travel, all as more clearly shown and described in the above mentioned co-pending application. The screen *b*, (mounted in the frame *k*) is rotated from a power connection with the pulley *g* through the gearing *h* and *i* in an obvious manner.

The arrangement of the structure for mounting the tank and vibrating the same will now be specifically described.

At each end of the frame *k* there is a cross-piece *p* supported at each of its ends on the frame. Above each cross-piece *p* is another cross-piece *q* distanced therefrom by rigid posts *r* and *s* placed at the ends thereof. The ends of the cross-pieces *p* and *q*, together with the posts *r* and *s*, are fixed firmly to the frame *k* by suitable bolts, as shown clearly in Fig. 1. The cross-pieces are thus supported at their ends only to the frame. They may be made of any suitable springy material which will allow a limited movement of the middle portions when the ends are rigidly supported.

Applicant has found that cross-pieces made of hickory give the best results because there is no tendency for the parts to crystallize after a great number of vibrations.

The tank *d* is fastened to the middle portions of the cross-pieces *p* and *q* by the bolts *t*. It will thus be seen that the tank is suspended in position below the rotating screen *b*. If now, the tank is given a vibrating movement of limited extent while the screen cylinder *b* rotates partly submerged in the pulp of the tank, practically the same result will be obtained as if the screen were given the vibrating movement as well as the rotary movement. The screen openings will thus be kept clear.

A cam-shaft *m* is mounted in the frame *k* and a cam *n* at each end of the machine bears against the wear-block *o* fastened to the lower cross-pieces *p*. As shown, one rotation of the shaft *m* forces the tank supporting the cross-pieces *p* and *q*, (and thus

the tank *d*) up and down four times. The continued rotation of the shaft *m* (driven in the manner shown in Fig. 2) vibrates the tank *d* thus sucking the pulp through the 5 screen openings and keeping the latter clear.

The weight of the tank, and the flexibility of the cross-pieces *p* and *q*, cause the cams *n* to be followed to about the right degree. The weight of the tank is supported by the 10 cross-pieces and not by the cam, which is designed to operate the tank without supporting it.

The preferred form of the apparatus has been described for purposes of illustrating 15 one embodiment of the invention and not for the purpose of limiting the invention to the one form shown and described. For example, the tank *d* could be supported and moved in many other ways with substantially the same results.

What I claim, is:—

1. A screen apparatus comprising in combination a containing tank adapted to hold the material being screened, a frame, resilient means constructed to support the tank from the frame, said tank being otherwise disconnected from the frame, a screen member mounted on the frame to occupy a position within the tank but spaced apart 25 therefrom, means to feed material to the screen member and mechanism to rapidly jog the tank whereby it is rapidly oscillated, due to its resilient supporting means.

2. A paper pulp screen apparatus com-

prising, in combination, a shallow tank 35 adapted to hold paper pulp, leaf-spring members attached to said tank at their middle portions, a frame having means to firmly attach the ends of said leaf-spring members, whereby the tank is yieldingly supported, a 40 rotatable, inclosed screen having means to feed pulp to the interior thereof, together with devices for rotating the screen and vibrating the suspended tank, whereby the screen openings are kept clear while submerged in the pulp of the tank. 45

3. A paper pulp screen apparatus comprising, in combination, a supporting frame, two horizontally arranged spaced spring-members mounted at each end of the frame with the ends thereof firmly fastened to the frame and with the middle portions free, a shallow tank constructed to hold pulp supported and fastened to the middle free portions of the spring members, a rotatably mounted inclosed screen with means to feed pulp to the interior thereof arranged to rotate while partly submerged in the tank, a cam-shaft arranged under the tank-supporting springs, having cams adapted to vibrate the tank through its spring support, whereby the screen openings are kept clear while they are submerged in the pulp of the tank. 55
